UNITED STATES PATENT OFFICE

2,101,479

NIGHT TARGET RANGE FINDER

Cleveland H. Schenk, Springfield, Ill.

Application March 22, 1935, Serial No. 12,342

2 Claims. (Cl. 240—6.41)

My invention relates to night target markers and more especially to targets for guns for officers of the law; an object being in my device to provide a more practical and convenient target 5 marker for night service than that one for which I filed patent application November 2, 1934, bearing Serial No. 751,191.

A purpose of my invention is to put to use some more refined improvements in such target 10 markers, which I have devised and which I have found to be both practical and economical to build and operate, as well as to be convenient to manipulate.

A particular purpose of my improved device 15 is to provide a new means of marking a night target, a better illumination for the target and greater convenience in the manipulation of the target marking light.

I attain the objects of my invention with the 20 device described in the annexed specification, recited in the claims and illustrated in the accompanying drawings in which like reference numerals indicate like parts in the several figures.

Referring to the figures:

25 Figure 1 is a longitudinal half-section of the rifle or riot gun type of target range finder of my invention.

Figure 2 is a front view of the device shown in section in Figure 1.

30 Figure 3 is a cross section of my device taken from 3 to 3 on Figure 1.

Figure 4 is a perspective of the mounting ring adapted to hold the screw shown in Figure 3 by which adjustments are made in the position of 35 the light in the top compartment of my night range finder.

Figure 5 is a rear view of the control switch for the lights used in my invention.

Figure 5a is a vertical half section of the 40 switch as viewed from the right of Figure 5.

Figure 6 is an enlarged detail of the terminal from the batteries adapted to contact with the control switch.

Figure 7 is a longitudinal half section of the 45 revolver type of target range finder of my invention.

Figure 8 is a front view of the device shown in Figure 7 in section.

50 Figure 9 is a perspective of the mounting ring adapted to adjustably support the target range finding light bulb in the upper compartment of my invention.

Figure 10 is a perspective of the plate used 55 ahead of the batteries for supporting the metallic

contact with the light bulbs in this form of the invention.

Figure 11 is a perspective of the control switch adapted to operate the lights in this form of my invention.

Figure 12 is a perspective illustrating the operating advantages of my invention when in the hand of an officer of the law at night. The target range finder throws a strong spot of light on the spot where a bullet from a rifle or riot gun may 10 be expected to hit when the light and gun sight are properly adjusted for its operation.

Referring now to the details of construction of my improved target range finder, I provide a casing 1 having an upper compartment 2 and 15 a lower compartment 3. This casing is adapted to be resiliently and slidably secured to a gun barrel as is shown in Fig. 12 by sliding this grip member 4 back on the barrel of the gun and this grip member is slidably held in groove 5 for 20 the support of casing 1.

In the upper compartment, I provide in an adjustable mounting 6 a plano-convex lens 7 mounted in the forward end of compartment 2 for the purpose of focusing the illumination from 25 light bulb 8 to a bright spot of light shown at 9 in Figure 12. This light bulb has a reflector 10 in which it is adjustably mounted and which is in turn mounted for further adjustment in a ring 11 supporting adjusting screws 12, 13, 14 30 and 15 adapted to be used for the lateral adjustment either up or down or sidewise of light 8 when focusing the spot of light where it is desired to throw it.

These screws are each mounted in ring 11 in 35 cross wise slots so as to permit the desired lateral adjustment of light bulb 8 which they support.

In addition to this convenience provided in top compartment 2 I also provide a reflector tube 16 40 shaped in a manner making the same smaller at the forward end than it is at the rear end in diameter with its inner surface polished so that when the light coming from bulb 8 is thrown forward by reflector 10 this illumination as it leaves 45 the casing through lens 7 throws a stronger light around the focused spot of light 9 (see Fig. 12) thus enabling the officer using the same to better observe the target and its surroundings. At the rear of casing 1 is a detachable closure 17 adapted 50 to seat over pin 18 and snap into hole 19 where the hole in pin 20 is resiliently held in place by a spring 21.

The lower compartment 3 supports a forward lens 22 adjustably mounted in a supporting ring 55

23 which also supports a reflector 24 and a light bulb 25.

Batteries 26 and 27 supply the current for bulbs 8 and 25 and are operatively contacted with each other by contact member 28 while bulb 25 makes a constant resilient contact with strip 29 while the current from batteries 26 and 27 passing through wire 30 back to the rear of casing 1 makes resilient contact with switch member 31 through wire 30.

As an explanation of the switch control lights 8 and 25 it may be said that the single control member 34 is adapted to be slidably moved in a slot 41 in insulating plate 37 and this control member has a contact end 38 pressing against the switch members 33, 39 and 40; as the single contact member 32 touches the battery 26.

It will thus be noted that when it is desired to turn on light 8, then the switch control member 34 will be slidably moved over to contact switch member 40 so that this member 40 may be placed over against contact member 35 which will carry the battery current to light 8. Where it is desired to have both lights 8 and 25 on at the same time, then switch control member 34 is moved over in slot 41 far enough to press against switch member 39 in the middle moving the same out to meet contact members 31 and 35 which will carry current to bulb 8 and bulb 25 but where it is desired to turn on only bulb 25, then the switch control member 34 is moved over in slot 36 far enough to meet switch member 33 causing the same to meet switch contact member 31 carrying the battery current from member 32 through contact member 31 by touching switch member 33.

It will be noted that the battery contact 32 and the switch members 33, 39 and 40 are all integral, while switch member 40 touches contact 35 when pressed into engagement therewith, switch member 39 touches both contact members 31 and 35 when pressed into engagement therewith by slidably moving control member 34 and switch member 33 touches contact member 31 when turning on light 25.

It will be observed that when screws 12, 13, 14 and 15 rest in cross slots 36, 37, 38 and 39 that any lateral adjustment desired may be made in the supported position of light 8 and reflector 10. In this lower compartment is also mounted a partition and conductor member 40.

In Figure 7 will be observed the revolver type form of my casing wherein the grip member 4 slidably engages a revolver barrel not shown as this grip is slidably adjusted in groove 5.

In this form of my casing, I secure the plano-convex lens 7 in the forward end of upper compartment 41 in connection with which I provide the reflector tube 42 extending from lens 7 back to the mounting for bulb 43 which is mounted for lateral adjustment in ring 44 having adjusting screws 45 and 46, with screws 47 and 48 not shown.

In ring 44 screws 45, 46, 47 and 48 are respectively mounted for adjustment in slots 49, 50, 51 and 52.

The shape of this casing requires an arrangement of the batteries 53 and 54 in a manner permitting battery 53 to be supported in the upper compartment 41 of this casing 55 with battery 54 resting parallel with battery 53 but in lower compartment 56 of this casing the closure member for this casing is the same in construction as closure 17 for the first form of my invention

shown in Fig. 1 and will be so designated while the latch members are the same.

I provide a lower light bulb 57 mounted in socket 58 at the forward end of lower compartment 56 in casing 55 while I provide a partition plate 59 rearward of bulbs 43 and 57 and forward of batteries 53 and 54 to provide a partition between the batteries and light bulbs as an insulation member and yet to support the contact member 60 which establishes connection between batteries 53 and 54 and bulbs 43 and 57.

I secure a series connection between batteries 53 and 54 through contact strip 61 which conducts the current from the forward end of battery 54 back between them to the rear end of battery 53.

Thus it will be observed that in this type of my invention, while it would be convenient and practical to have the lights turn on one at a time yet it is thought that it will be most desirable to have both lights in most cases turn on at the same time.

Switch contact member 62 is made to contact with battery 54 and is turned on by switch control knob 63 mounted in closure member 17.

It will be observed in connection with my invention that I provide in the electric light bulbs 8 and 43 for instance, a filament that is peculiarly designed and effective for this invention; wherein the filament being coiled from one end to the other in the direction longitudinally aligned with the tube in which it is mounted. Thus by coiling this filament in alignment with the reflector tube there is secured on the bright spot of light a circular image of the filament making the focused spot of light more readily observed.

It will be noted also that lens 7 is especially manufactured for this particular target range finder and this lens is shaped in a manner making it flat on one side and also flat on the other side with the exception of a central smaller middle portion which is convex. The purpose of this type of lens seen used with reflector tube 16 is to provide means for throwing the illumination which passes through this lens much more brightly and greater around the focused spot of light, thus better illuminating the target and its surroundings.

With this construction this invention establishes a substantial improvement over the novel features shown, described and claimed in my former application and what I claim in this new and improved invention and desire to have protected, is:

1. A night target range finder for guns comprising a two compartment casing provided along the top with an elongated resilient grip slidably secured to the casing for engaging a gun barrel for the support of the casing, the upper of said compartments in the casing provided with a light, an adjustable mounting for the light, with a plurality of adjusting screws; said mounting with said light disposed adjacent the rear of the top compartment in the casing, a lens adjustably mounted in the forward end of said upper compartment; said lens having a central concentrating portion and a peripheral portion having plane parallel faces and an adjustable reflecting tube extending a major portion of the distance from said lens to said light and having a greater diameter at the rear end than the front end, an integral second and lower compartment in said casing, an electric light mounted adjacent the forward end of said compartment, and lens means cooperating with said light, batteries mounted in

5 said casing and operatively connected with both of said electric lights and an electric switch operatively connected in the circuit between said batteries and said lights for the selective control of said lights; whereby the operator may turn on either light by itself or both lights together and whereby said upper light with its lens may focus a bright spot of light on a target and whereby a flood of light may be thrown about said focused spot of light when desired.

10 2. A night target range finder for guns comprising a two compartment casing provided along the top with an elongated resilient grip slidably secured to the casing for engaging a gun barrel for the support of the casing, the upper of said compartments in the casing provided with a light, an annular mounting band for the support of the light and provided with a plurality of transverse slots, adjusting screws supporting the light and respectively held in said slots for the selective lateral adjustment of the light; said mounting with said light disposed adjacent the rear of the top compartment in the casing, a

15 lens adjustably mounted in the forward end of said upper compartment; said lens having a central concentrating portion and a peripheral portion having plane parallel faces and an adjustable reflecting tube extending a major portion of the distance from said lens to said light and having a greater diameter at the rear end than the front end, an integral second and lower compartment in said casing, an electric light mounted adjacent the forward end of said compartment and lens means cooperating with said light, batteries mounted in said casing and operatively connected with both of said electric lights and an electric switch operatively connected in the circuit between said batteries and 20 said lights for the selective control of said lights; whereby the operator may turn on either light by itself or both lights together and whereby said upper light with its lens may focus a bright spot of light on a target and whereby a flood of light may be thrown about said focused spot of light when desired.
